INVENTOR,

George R. Paranteau
BY *Alfred E. Brown,*

ATTORNEYS.

UNITED STATES PATENT OFFICE.

GEORGE R. PARANTEAU, OF OXNARD, CALIFORNIA.

FRUIT-PITTING MACHINE.

Original No. 1,392,518, dated October 4, 1921, Serial No. 411,841, filed September 21, 1920. Application for reissue filed December 15, 1922. Serial No. 607,248.

To all whom it may concern:

Be it known that I, GEORGE R. PARANTEAU, a citizen of the United States, residing at Oxnard, in the county of Ventura and State 5 of California, have invented new and useful Improvements in Fruit-Pitting Machines, of which the following is a specification.

This invention relates to fruit pitting machines and has for its object the provision of 10 novel means for holding fruit to be pitted and carrying it into engagement with a fruit splitting knife which is also operative to arrest the pit to dislodge it from the fruit while the fruit is twisted or partially twisted 15 with relation to the pit to cause a severance of the fiber from the pit.

It is an object of this invention to provide novel fruit engaging elements coacting to hold fruit associated with means for moving 20 the fruit holding elements into such relation to a knife that the knife will engage the fruit at a point midway between the holders and thus insuring that the knife shall engage the fruit at its center and so position 25 the fruit with relation to the knife as to cause the knife to engage the pit and operate most effectively.

It is a further object of this invention to produce novel means for successively retracting 30 the fruit engaging elements and for then releasing them in order that they may be caused to embrace the fruit and carry it into operative relation with the knife.

It is a further object of this invention to 35 provide a fruit carrier capable of delivering fruit one at a time to the holders which coact with the knife for splitting the fruit and removing the two halves thereof from the pit.

With the foregoing and other objects in 40 view, the invention consists in the details of construction and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a front elevation of a machine embodying the invention with a few of the elements in advance in section;

Figure 2 illustrates an end elevation;

Figure 3 illustrates a sectional view on the line *a—a* of Fig. 1; and

Figure 4 illustrates a sectional view on the line *b—b* of Figure 1;

In these drawings I have illustrated what might be termed "right and left hand members" identified by the letter A, and except 60 as to slight details of construction as will presently appear, the right hand and left hand members are practically duplicated and corresponding parts of the right hand element cooperate with the like parts of the 65 left hand element in carrying fruit and presenting it to a knife in conjunction with which both elements coact.

The machine will be described as having a plurality of fruit carrying members, but 70 it is to be understood that one or such additional members or pairs of fruit carrying elements may be employed, and the inventor does not wish to be restricted with respect to the number comprised in a machine.

The invention as embodied in the illustration includes a series of elastic cups 1, each of which has a flange 2 and each said cup is carried by a plunger 3 slidably mounted within a tube 4 which tube contains 80 a spring 5 which bears against the inner end of the tube and against the plunger. A pin 6 extends through the rear end of the tube and operates as a guide therefor, as will presently appear. The tube 4 has a 85 flange 7 and the said tube 4 is slidably in a hollow spindle 8 having a spring 9 therein bearing against the inner end of the tube 4. Each spindle also has a plug 9^a in its end against which the spring 9 bears to hold it 90 under compression. Each hollow spindle 8 has a pinion 10 on the end remote from the cup and each spindle is rotatably mounted in a bearing 11 cast in the wheel 16. A pin 12 extends through the plunger and may 95 slide in the slots 13 of the tube 4 for a purpose to be presently explained. Each spindle 8 has slots 15 therein in which the pin is guided and therefore, each plunger may be free to move inwardly against the 100 action of a spring 5 and each tube may have movement in the hollow spindle against the action of a spring 9.

The wheel 16 which has the bearings is mounted on a shaft 18, and a wheel 17 having a toothed periphery also carries bearings

2. in which hollow spindles are applied for the right hand member of the machine.

The shaft 18 has a pulley 19 for receiving power for driving the shaft, or other suitable power transmitting means may be supplied as a substitute. The shaft is intended to be rotated in the direction of the arrow *f* for carrying the fruit holding elements successively to positions indicated by the letters C, D, E and F, as shown in Figs. 1 and 2. Fig. 3 illustrates the elements or fruit holders in position in advance of those shown in Figure 2 by about 50 degrees of rotation, and in Fig. 1, as shown, the positions C and F are the positions in which the cups are open to release fruit previously held in the positions D and E. In other words, the positions D and E are those prior to the time the fruit encounters the knife, whereas the other positions are those in which the fruit has been subjected to the action of the knife and thereafter released from the holders. Guiding bars G are shown as stationed on the frame H and they are curved so that their inner edges are substantially concentric with the wheels 16 and 17 but they are offset laterally to form cams 20 which are effective to move the plungers outwardly or away from the center of the machine after the fruit has passed the knife 25, which is anchored to the base H as fully shown in Fig. 3, an action which results in releasing the fruit held by the cups. The plungers after being fully separated travel in parallel paths until the opposite ends 21 of the guiding bars are reached and then the plungers are released and the springs of the plungers become effective to force the plungers into engagement with the fruit carried by the conveyer cups as will presently appear.

The conveyer includes a sprocket wheel 35 which is rotated in the direction of the arrow *g*, a sprocket chain 36 traveling thereover which travels in the direction of the arrow *d*, the said sprocket chain being provided with a plurality of pockets 37 on which fruit is lodged and carried into position where they may be engaged by the cups. The conveyer wheel 35 is mounted on a shaft 35^a driven by a train of gearing 32, 33 and 34 from the wheel 17, and of course the gearing is so proportioned as to time the conveyer and transfer the fruit carrying pockets 37 under a pair of cups at the time the cups are released from the guiding bar, the said position being indicated by the letter D in Fig. 1.

It is desirable that the central part of the fruit being carried by the cups be presented to the knife, and to that end, a centering mechanism B is employed which moves the cups carrying the fruit simultaneously in the same or corresponding directions to the right hand or left hand side and this cen-

tering mechanism includes channel members 26 having their outer ends flared and their inner ends converging. The channel members 26 are carried respectively as at 27^a by racks 27 having oppositely disposed teeth which are engaged by a pinion 28 and the said pinion is mounted on a U-shaped plate 29 held in place by the standards 30. These racks 27 thus carry, each, one of the channel members 26, as shown in Figure 1, each channel member being movable jointly with the rack upon which it is mounted and movable relative to the other rack and channel member. The devices on the left hand and right hand members are set to work opposite each other and the cups are intended to hold the fruit midway between them as near as possible, taking into account the irregular shape of the fruit. The cups are rotated or spun in the direction of the arrow *e*, Figs. 2 and 3, while being carried by the wheels 16 and 17 in the direction of the arrow *f*.

The spinning action of the cups presents the fruit to the knife while it is rotating, thus making it possible for the knife to split the fruit and as the fruit is carried beyond the knife, the pit is arrested and separated from the fruit.

The channel members 26, of course, move the spindles as stated and the flanges 2 of the plungers are relied on for engaging the sides of the channel members so that as the cups travel toward the knife, the position of the cups may be shifted to present the substantial center of the fruit to the knife. The racks 27 have guides 31 which are in the sides of the U-shaped plate 29. The channel members 26 are held by reason of their connection with the racks 27 in engagement with the pinion 28 at all times approximately centrally located with respect to the knife 25, while being at the same time free to move in either direction toward or away from each other in equal degrees each, and hence fruit of different sizes may be accommodated. No alternative movement is allowed the racks and they must move in synchronism. In other words, an inward movement of one and an outward movement of the other at the same time will not be permitted, but they must move together inwardly or outwardly. An outward movement is understood as being a movement away from the center between the channels and by inward movement is meant a movement toward the center. The centralized position of the channel members 26 is seen to be always maintained through the action of the racks and pinion, and therefore, the flanges 2 of the fruit holders in passing through the channels must be centralized by such passing and the cups 1 with the fruit held likewise centralized with respect to the knife as required.

It will be obvious that fruit of different sizes may be accommodated by the channel members 26 and the other features of the centering means or mechanism B. As pieces 5 of fruit of varying diameters are successively engaged by cups 1, the flanges 2 of such cups will of course be caused to assume positions of correspondingly varying relative separation. If the center of the fruit is not 10 in the plane of the knife 25 which is to sever the fruit and discharge the pit, one of the flanges 2 will be further to one side of such plane than the other of such flanges, and one such flange will act upon the corresponding channel member 26 to move it 15 either inwardly or outwardly, the other channel member being caused to move an equal distance in the opposite direction through the co-action of the racks 27 and pinion 28. When the channel members have 20 been thus moved, either away from or toward each other sufficiently to cause the flanges 2 of both cups to be engaged with their respective channel members, the cups 25 will be guided and directed by such channel members jointly, either in one direction or the other, until the fruit between the cups is brought at its center into the plane of the knife 25. This must follow, inasmuch as 30 the racks and their separately supported channel members cannot move in the same direction. Both, as stated, must perform movements toward the plane of the knife or away from it. Being thus locked against 35 movement in the same direction transversely of the machine, the cups must be guided down to position to present the center of the fruit within the plane of the knife 25, resultant upon the particular relative separation of the cups which corresponds to the particular diameter of the particular piece of fruit between the cups. When the next pair 40 of cups is advanced toward the centering mechanism, if the fruit be of different dimensions, the centering mechanism will execute a performance similar in kind to that just described, all as controlled by the particular dimensions of the piece of fruit concerned.

50 It is believed unnecessary to supply a résumé of the operation of the device since a description of the operation of the elements and their coaction with other elements has been stated in connection with a description of the elements.

Having thus disclosed my invention, I claim and desire to secure by Letters Patent:

1. In a fruit pitting machine, rotatably mounted wheels in spaced relation to each other, fruit carrying members carried by the wheels, the fruit carrying element of one wheel being oppositely disposed with relation to the fruit carrying element of the other wheel, each of the said fruit carrying elements comprising a cup, a plunger carry-

ing the cup, means for urging the plunger outwardly, means for rotating the plunger, means for pressing the plunger inwardly against the action of the means for urging the plunger outwardly, a knife in position to engage fruit between the cups as the cups are carried, and means for guiding the coacting cups in a right hand or left hand direction. 70

2. In a fruit pitting machine, a shaft wheels mounted thereon in spaced relation to each other, a fruit engaging element carried by one of the wheels, a fruit engaging element carried by the other wheel opposite the first mentioned fruit engaging element, the said fruit engaging elements being 80 adapted to coact for carrying fruit, each of the said fruit engaging elements comprising a cup, a plunger carrying the cup, means for yieldably holding the plunger in operative relation to the wheel which carries it, a 85 guide for each plunger having a camming surface for moving the plunger inwardly against the action of the spring, a conveyer having fruit carrying elements operative to deliver fruit between the two coacting cups, 90 a knife in the path of travel of fruit carried by the fruit engaging cups in their rotation, means for imparting rotary motion to the fruit engaging cups when carried by the wheels, and means for centering the fruit 95 held by the cups with relation to the knife.

3. In a fruit pitting machine, rotatably mounted wheels in spaced relation to each other, fruit engaging members carried by the wheels, the fruit engaging members of one wheel being oppositely disposed to that carried by the other wheel and adapted to coact with each other for holding and carrying fruit, each of said fruit engaging elements including a cup for embracing the fruit, means for yieldingly supporting the cup with relation to the wheel, means for rotating the cup as the wheel travels, a knife in the path of travel of fruit carried by the cups, and means for moving the cups for 110 centering the fruit with relation to the knife.

4. In a fruit pitting machine, rotatably mounted wheels, fruit grasping members carried by the wheels, the fruit grasping member of one wheel being movable toward and away from the fruit grasping member of the other wheel, means for yieldingly maintaining the grasping members in operative relation to each other, means for rotating the wheels, and means for simultaneously shifting the fruit grasping members in corresponding directions. 115

5. In a fruit pitting machine, rotatably mounted wheels, yieldable and coacting fruit grasping members carried thereby, means for guiding the said fruit grasping members laterally of the machine in the same direction simultaneously, means for coupling the guiding means whereby they 120

work in unison, and means for rotating the wheels.

6. In a fruit pitting machine, fruit grasping elements, means for carrying the fruit grasping elements, a conveyer operative to convey fruit in the path of travel of the fruit grasping elements, whereby the said fruit grasping elements will move fruit from the conveyer, means for mounting the fruit grasping elements yieldably, whereby they move toward and away from each other, means for centering the fruit carried by the fruit grasping elements, and a knife in the path of travel of fruit held by the fruit grasping elements.

7. In a fruit pitting machine, fruit grasping elements, means for yieldingly mounting the fruit grasping elements in opposed relation to each other for coaction one with the other, means for simultaneously carrying the fruit grasping elements, and means for moving the fruit grasping elements in the same direction simultaneously transversely.

8. In a fruit pitting machine, fruit grasping elements, means for yieldingly mounting the fruit grasping elements in opposed relation to each other for coaction one with the other, means for simultaneously carrying the fruit grasping elements, means for moving the fruit grasping elements in the same direction simultaneously transversely, and a knife in the path of travel of fruit carried by the said fruit grasping elements.

9. In a fruit pitting machine, fruit grasping elements, means for yieldingly mounting the fruit grasping elements, means for carrying the fruit grasping elements in opposed relation to each other for coaction one with the other, guides for moving the fruit grasping elements simultaneously in one direction or the other transversely of the ma-

chine, means on each fruit grasping element for engaging a guide, and means for communicating the motion of one guide to the other guide.

10. In a fruit pitting machine, fruit grasping elements, means for yieldingly mounting the fruit grasping elements, means for carrying the fruit grasping elements in opposed relation to each other for coaction one with the other, guides for moving the fruit grasping elements simultaneously in one direction or the other transversely of the machine, means on each fruit grasping element for engaging a guide, means for communicating the motion of one guide to the other, means for urging the fruit grasping elements normally toward each other, and means for pressing the fruit grasping elements apart.

11. In a fruit pitting machine, yieldable coacting fruit grasping members, means for moving the said members into operative relation with a knife, and means for simultaneously shifting the fruit grasping members in corresponding directions.

12. In a fruit pitting machine, fruit grasping members arranged in pairs, means for carrying the fruit grasping members of a pair in unison, means for simultaneously rotating the fruit grasping members of each pair, and means for simultaneously shifting the fruit grasping members in corresponding directions axially.

In witness whereof, I have signed my name to this specification in the presence of the subscribing witnesses.

GEORGE R. PARANTEAU.
